UNITED STATES PATENT OFFICE.

JAMES A. DAVIS, OF WASHINGTON, DISTRICT OF COLUMBIA.

HORSESHOE ATTACHMENT.

1,142,028.

Specification of Letters Patent.

Patented June 8, 1915.

Application filed August 26, 1914. Serial No. 858,657.

To all whom it may concern:

Be it known that I, JAMES A. DAVIS, citizen of the United States, residing at Washington, in the District of Columbia, have 5 invented certain new and useful Improvements in Horseshoe Attachments, of which the following is a specification.

My invention relates broadly to new and useful improvements in horse shoes, and has 10 particular reference to the provision of a detachable metallic sole which may be secured to the shoe in such manner as to prevent the frog of the horse's hoof from striking rocks or the like.

15 The principal object of my invention is to accompany the detachable metallic sole with a number of detachable calks and a novel and simple type of fastening means which will serve to secure and firmly attach the 20 sole to the horse's hoof.

In connection with the above stated object, I aim to eliminate from the sole fastening means, all bolts and nuts, employing but two screw rods for securing not only the 25 calks, but for also securing the sole in the proper position against the horse shoe.

A further object is to construct the sole plate in two separately formed sections which are adjustably connected whereby the 30 sole may be applied to shoes of varying sizes.

An object of equal importance with the foregoing is to construct the sole and accompanying parts with such regard to proportion, arrangement, and general design, that they may be cheaply manufactured, will be durable and efficient in service and may be readily attached to any size of horse shoe within a reasonable range.

40 The above recited and other incidental objects of a similar nature, which will be hereinafter more specifically treated, are accomplished by such means as are illustrated in the accompanying drawings, described in 45 the following specification, and then more particularly pointed out in the claims, which are appended hereto and form a part of this application.

With reference to the drawings, wherein 50 there has been illustrated the preferred embodiment of this invention as it is reduced to practice, and throughout the several views of which similar reference characters designate corresponding parts, Figure 1 is 55 a bottom view illustrating the sole plate and the accompanying parts in assembled

position on a horse's hoof, Fig. 2 is a detail perspective view of the sole plate, calk members, and fastening devices in operative assembled relation to each other before application to the horse's hoof, Fig. 3 is a side elevation of the horse's hoof showing the invention applied thereto, Fig. 4 is a detail rear elevation partly in section of the device removed from the horse's hoof. The section shown in this figure is taken on the line 4—4 of Fig. 1, Fig. 5 is a section on the line 5—5 of Fig. 1, Fig. 6 is a detail perspective view of one of the heel calks and the fastening means employed in holding the calk in the proper position, and Fig. 7 is a detail fragmentary perspective view of a modified form of sole plate.

As best shown in Fig. 2 of the accompanying drawings, the body portion of the device is formed in the nature of a sole plate which is comprised of two separate sections 10 and 11. The section 10 is preferably formed from two separate metal plates, one of which, indicated individually by the numeral 12, is substantially semi-circular in outline and the other of which, designated by the numeral 13, is substantially rectangular, being provided, however, with curved end edges. The straight edge portion of the member 12 overlaps and bears against the upper face of the forward edge portion of the member 13, being held in the proper position thereon by means of rivets or similar fastening devices, indicated at 14. While the section 10 of the sole plate is preferably formed from two separate metal plates, it may, of course, be formed as an integral unit in the manner shown best in Fig. 7. Upon reference to this figure, it will be seen that the modified form of the member 10 is formed from a single metallic plate which is bent along a transverse line so as to dispose its rear portion 15 in a plane which is below and parallel to the plane of its forward portion 16.

The section 11 of the sole plate is formed from a single sheet of metal which is folded on a transverse medial line so that the member 11, when completed, includes upper and lower body plates 17 and 18. The central portion of the sheet of metal from which the member 11 is formed is shaped over a former to produce box shaped brackets or housings 19 and 20, which are separated by a slot 21, as shown in Figs. 1 and 2. The purpose of this slot is to permit access to

the heel calk screw rod as will be hereinafter more fully explained. The member 11 is cut away between the members 19 and 20 and its adjacent terminals, so as to form the V-shaped notches or openings 22. These openings 22 are provided to receive the rear calks as will also be hereinafter more fully explained.

In connecting the sections 10 and 11, the 10 forward edge of the member 11 is placed upon the upper face of the plate 13 and is engaged against the rear edge of the member 12. The screw bolt, indicated at 23, is then passed through the members 11 and 13. 15 A pair of apertures 24 is preferably provided for the member 11 so that the sections may be adjusted to accommodate the sole to horse shoes of different sizes.

The forward edge portion of the plate 12 20 is cut away along a chordal line 25 so that the transversely extending toe calk 26 may be flatly engaged against the edge of the member 12. Formed integrally with the toe calk 26 and extending rearwardly from the 25 upper edge thereof is a shoulder plate 27 which is substantially U-shaped and is held in position against the upper face of the member 12 by means of screw bolts 28, as best shown in Fig. 2. It should be noted 30 that the lower face of the member 27 lies in the same plane as the upper edge 29 of the toe calk. Thus, the edge 30 of the member 27 constitutes a substantially semi-circular shoulder which is adapted to engage against 35 the inner edge of the horse shoe, as will be hereinafter explained.

It is to be noted that a substantially T-shaped slot or opening is formed in the approximate center of the member 12. The 40 head portion of this opening, designated by the numeral 31, extends transversely of the plate and the stem portion 32 of the slot extends longitudinally with respect to the plate. The arms of the U-shaped member 45 27 are arranged so that their inner edges align vertically with the edges of the portion 32 of the slot.

As a means for detachably securing the 50 forward terminal of the sole plate in position against the horse shoe, I employ a yoke member 33 which is substantially U-shaped and is adapted to pass transversely across the toe of the horse's hoof, as best shown in Fig. 3. The terminals of the yoke 33 are 55 bent at right angles so as to lie in a horizontal plane, as indicated at 34. These portions 34, which will be hereinafter referred to as the arms of the yoke, extend diagonally toward the center of the shoe, as shown 60 in Fig. 1, and are connected by an integral transversely disposed bar 35. This bar 35 bears against the lower face of the member 12, as shown in Figs. 3 and 5 particularly. Formed integrally with the bar 35 and at 65 the approximate center thereof, is an up-

standing lug 36 which is provided with a threaded bore adapted to receive a screw rod 37. The lug 36 serves not only to receive the screw rod 37 by means of which the yoke is drawn into clamping engagement with the horse's hoof, but also serves as a guide member for the yoke. In this connection, it is to be noted that the lug is in width equal to the width of the stem portion 32 of the T-shaped slot, so that when 70 the lug is moved longitudinally through the slot, its side faces will engage against the edges of the slot and cause the yoke to extend, at all times, at right angles to the longitudinal axis of the sole plate. The 75 screw rod 37 is rounded at its forward terminal and seats in a socket 38 formed in the inner edge of the member 30 at the approximate center thereof. The head 39 of the screw rod is provided with a number of 80 radial bores 40 in which may be inserted a nail, screw driver, or any other similar element for rotating the screw rod. It will be observed, particularly upon reference to Fig. 1, that when the screw rod 37 is threaded 85 through the lug 36, the yoke 33 will be drawn toward the sole plate and engaged with the horse's hoof. At the same time the threading of the screw rod through the lug, will cause the spacing of the lug from the 90 member 27 and as a result, the shoulder 30 of this member will engage firmly against 95 the inner edge of the horse shoe.

The rear portion of the sole plate is held 100 in the proper relation to the horse shoe by a pair of laterally extensible clamping plates 41 and 42 which are formed at the terminals of and integrally with a pair of internally threaded sleeve members 43 and 44. These 105 members 43 and 44 are slidably received within the members 19 and 20 and are, therefore, made substantially rectangular in cross-section, so that they will be held against 110 rotation within these brackets or housings 19 and 20. A screw rod, indicated at 45, is provided with a square centrally disposed portion 46 which is located in the slot 21 when the terminals of the member 45 are 115 threaded into the members 43 and 44. It will, of course, be obvious that the terminal portions of the screw rod 45 are oppositely threaded, that is, one is provided with a left hand thread while the other is provided with a right hand thread, so that the rotation 120 of the member 45 in one direction will cause the clamping plates 41 and 42 to move outward while the rotation of the member 45 in the other direction will cause the plates to be drawn inwardly. Extending laterally from the lower edge portion of each 125 of the members 41 and 42 is a tapered spindle 47. On each of these tapered spindles 47 is mounted a heel calk 48. The members 48 are preferably triangular in shape and are provided with single centrally located 130

openings 49 which receive the spindles 47. The calks 48 are, or course, of such size that the distance from the openings 49 to the edges of the calks is less than the distance from the spindles to the upper edges 5 of the members 41 and 42. By thus proportioning the heel calks, the upper portion of each of the members 41 and 42 is exposed for engagement with the inner edges of the 10 horse shoe at the heel portions thereof. It is now to be noted that the screw rod 45 may be readily manipulated to extend the members 41 and 42 so that their upper edge portions will clamp firmly against the heel 15 portions of the shoe, thus holding the sole plate against movement relative thereto. It is also to be noted that the heel calks are held against rotation on the spindles by the engagement of one of their edges with the 20 lower face of the horse shoe. The necessity of providing the V-shaped notches 21 and 22 in the rear edge of the member 11 will now become apparent for it will be seen that these notches are necessary to accommodate 25 the plates 41 and 42 and the calks 48.

Before concluding the description of my device, I desire to direct particular attention to the fact that the employment of nuts 30 in the fastening means of the sole plate is eliminated, the entire device being securely held in position on the horse shoe by means of but two screw rods. I have found in experiments conducted with other shoes both 35 of my own invention and those at present on the market, that a sole plate which is held in position by nuts almost invariably falls off the horse's hoof after being in use only a few hours. The extreme jars and vibration 40 to which the nuts are subjected when the sole plates are attached to heavy draft animals is such as to cause within a short time, the loosening of the nuts and their almost immediate loss. I also desire to direct 45 particular attention to the fact that the heel calks 48 may be turned upon the spindles so as to present at different times, each one of the corners to the road bed. Thus, the heel calks may be used for a relatively 50 long time before it is necessary to substitute new ones or to sharpen the old ones.

Having thus described the invention, what is claimed as new is:—

1. The combination with a horseshoe, of 55 a device of the character described including a sole plate, a longitudinally adjustable clamping yoke carried by the sole plate, and a pair of laterally extensible clamping plates carried by the sole plate and engageable 60 against the heel portion of the horseshoe for holding the sole plate in position thereon.
2. The combination with a device of the character described, of a sole plate formed in two adjustably connected sections, a 65 clamping yoke adjustable longitudinally

with respect to the sole plate and adapted to engage over the toe of a horse's hoof, and a pair of laterally extending clamping plates engageable against the heel portion of a horseshoe.

3. A device of the character described including a sole plate consisting of two adjustably connected sections, a shoulder plate adapted to engage against the inner edge of a horseshoe at the toe portion thereof, a 70 clamping yoke engaging the bottom face of the sole plate and adapted to embrace the toe portion of a horse's hoof, a screw rod threaded through the yoke member and engageable against the shoulder plate for moving the 75 yoke longitudinally with respect to the sole plate, and a pair of laterally extensible clamping plates carried by the sole plate and adapted to engage against the heel portions of the horseshoe.

4. A device of the character described including a sole plate consisting of two adjustably connected sections, longitudinally adjustable clamping means for holding the sole plate in position against a horseshoe, 80 and laterally adjustable clamping means engageable with the heel portion of the horseshoe for holding the sole plate in position thereon.

5. A device of the character described including a sole plate, a clamping yoke adjustable longitudinally thereof, a screw rod controlling the adjustment of the clamping yoke, a pair of sleeve members slidably connected to the sole plate and adapted to move laterally with respect thereto, clamping plates formed terminally of the sleeve members and adapted to engage against the heel portion of a horseshoe, and a screw rod controlling the adjustment of the sleeve members. 95

6. A device of the character described including a sole plate, a clamping yoke adjustable longitudinally thereof, a screw rod controlling the adjustment of the clamping yoke, a pair of sleeve members slidably connected to the sole plate and adapted to move laterally with respect thereto, clamping plates formed terminally of the sleeve members and adapted to engage against the heel 100 portions of a horseshoe, and a screw rod controlling the adjustment of the sleeve members, and a pair of heel calks removably mounted at the terminals of the sleeve members, said calks being adapted to bear 105 against the horseshoe at the heel portions thereof.

7. A device of the character described including a sole plate having a substantially T-shaped opening, a clamping yoke, a lug formed on the yoke and movable through the stem portion of said opening, a screw rod threaded through the lug, a shoulder plate carried by the sole plate and receiving the terminal of the screw rod, said shoulder 115

plate being adapted to bear against the inner edge of a horseshoe at the toe portion thereof, the head of the screw rod being positioned in the head portion of said opening, and a pair of laterally adjustable clamping plates adapted to engage against the heel portion of the horseshoe for holding the sole plate in position thereon.

8. In a device of the character described, 10 a sole plate consisting of two longitudinally adjustable sections, longitudinally adjustable clamping means for holding the sole plate in position on a horse's hoof, said means being adapted to embrace the toe portion 15 of a horseshoe at opposite sides thereof and the toe portion of a horse's hoof, and laterally adjustable means co-acting with the first-mentioned means and adapted to engage against the heel portion of a horse's 20 hoof.

9. A device of the character described including a sole plate, a longitudinally adjustable clamping yoke, a pair of housings formed on the sole plate at the rear terminal thereof, sleeve members slidably mounted in the housings, a screw rod connecting the sleeve members and operable for laterally adjusting the same, clamping plates formed on the terminals of the sleeves and 30 adapted to engage against the heel portions of a horseshoe, lateral spindles carried by the clamping plate, and a heel calk removably mounted on each of said spindles.

10. A device of the character described 35 including a sole plate, a clamping yoke mounted for longitudinal adjustment with respect to the sole plate and adapted to embrace the toe portion of a horseshoe and the toe portion of a horse's hoof, and a screw rod for controlling the adjustment of the clamping yoke.

11. A device of the character described including a sole plate, a shoulder plate carried by the sole plate, a clamping yoke mounted 45 for longitudinal adjustment with respect to the sole plate, and a screw rod bearing terminally against the shoulder plate and connected to the clamping yoke for controlling the adjustment of the same.

50 12. A device of the character described including a sole plate, a shoulder plate carried by the sole plate, a clamping yoke mounted for longitudinal adjustment with respect to the sole plate, a screw rod bearing terminally

against the shoulder plate and connected to 55 the clamping yoke for controlling the adjustment of the same, and independent laterally movable clamping plates carried by the sole plate and adapted to engage against the heel portions of a horseshoe for holding 60 the sole plate against displacement.

13. A device of the character described including a sole plate, a clamping yoke mounted for longitudinal adjustment with respect to the sole plate and at the forward end 65 thereof, a pair of bearing brackets formed on the rear terminal of the sole plate, a pair of internally threaded sleeve members mounted for sliding movement through the bearing brackets, a screw rod engaging in the sleeve members and operable for controlling the lateral adjustment of the same, and a pair of clamping plates carried by the outer ends of the sleeve members and adapted to engage against the heel portions 70 of a horseshoe.

14. A device of the character described including a sole plate, a clamping yoke mounted for longitudinal adjustment with respect to the sole plate and at the forward end 80 thereof, a pair of bearing brackets formed on the rear terminal of the sole plate, a pair of internally threaded sleeve members mounted for sliding movement through the bearing brackets, a screw rod engaging in 85 the sleeve members and operable for controlling the lateral adjustment of the same, a pair of clamping plates carried by the outer ends of the sleeve members and adapted to engage against the heel portion 90 of a horseshoe, laterally extending spindles formed integrally with the said clamping plates, and heel calks removably mounted on said lugs.

15. A device of the character described including a sole plate, a longitudinally adjustable clamping yoke, a pair of laterally adjustable clamping plates, laterally extending spindles carried by the clamping plates, and non-circular heel calks revolvably mount- 95 ed on the spindles.

In testimony whereof I affix my signature in presence of two witnesses.
